UNITED STATES PATENT OFFICE

122,656

DESIGN FOR A GRAVE MARKER

Gilford Duff Adams, Butterfield, Mo.

Application May 27, 1940, Serial No. 92,641

Term of patent 7 years

To all whom it may concern:

Be it known that I, Gilford Duff Adams, a citizen of the United States, residing at Butterfield, in the county of Barry and State of Missouri, have invented a new, original, and ornamental Design for Grave Markers, of which the following is a specification, reference being had to the accompanying drawing, forming part thereof.

Fig. 1 is a perspective view of a grave marker, showing my new design.

Fig. 2 is an end view of the grave marker.
Fig. 3 is a cross-sectional view thereof taken on the line 3—3 of Fig. 1.

I claim:

The ornamental design for a grave marker, as shown.

GILFORD DUFF ADAMS.
